(57) **CLAIM**

The ornamental design for a roll-on container, as shown and described.

DESCRIPTION

FIG. 1 is a front, right and top perspective view of a roll-on container, showing our new design;

FIG. 2 is a front, right and top perspective view thereof;

FIG. 3 is a rear, left and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a front, right and top perspective view thereof, shown without the bottle for ease of illustration;

FIG. 11 is a rear, left and bottom perspective view thereof, shown without the bottle for ease of illustration;

FIG. 12 is a front view thereof, shown without the bottle for ease of illustration;

FIG. 13 is a rear view thereof, shown without the bottle for ease of illustration;

FIG. 14 is a left side view thereof, shown without the bottle for ease of illustration;

FIG. 15 is a right side view thereof, shown without the bottle for ease of illustration;

FIG. 16 is a top plan view thereof, shown without the bottle for ease of illustration; and,

FIG. 17 is a bottom plan view thereof, shown without the bottle for ease of illustration.

The broken lines shown in the drawings illustrate portions of the roll-on container that form no part of the claimed design.

1 Claim, 17 Drawing Sheets
